DESIGN FOR A HYDRAULIC PRESS

William C. Denison, Jr., Powell, Ohio, assignor to
The Denison Engineering Company, Columbus,
Ohio, a corporation of Ohio

Application November 30, 1944, Serial No. 116,620

Term of patent 14 years

(Cl. D63—1)

To all whom it may concern:

Be it known that I, William C. Denison, Jr., a citizen of the United States, residing at Powell, in the county of Delaware and State of Ohio, have invented a new, original, and ornamental Design for a Hydraulic Press, of which the following is a specification, reference being had to the accompanying drawing, forming a part thereof, in which

The figure is a perspective view of a hydraulic press, showing my new design.

The side of the press, not shown, is substantially like the side shown.

I claim:

The ornamental design for a hydraulic press, substantially as shown and described.
